[57] ABSTRACT

In a preferred embodiment of the invention, a paper sheet holder composed of a rigid strip having a hole in each of opposite ends of a small diameter and each hole having spirally twisted thereinto a base end of a spiral coil spring, the opposite end of each spring having at least the last coil thereof twisted to serve as a hook coil for engaging the hook coil of the other spring, each of the two coil springs having a diameter greater than its respective hole into which it is twisted, and each spring being threaded though aligned hole of stacked sheets of paper having two holes spaced one from the other at opposite ends of the paper sheets, with the under side of the springs-mounted strip having a masking surface adhered thereto with a sheet rigid backing leaf mounted to the masking materials exposed surface.

3 Claims, 5 Drawing Figures

FILE FOLDER PAPER FASTENER

This invention is directed to a paper holder of one or more, preferably a stack of sheets each sheet having two spaced mounting holes along a common edge.

BACKGROUND TO THE INVENTION

Prior to the present invention, there have existed a variety of different types of paper mounts of the general type to which this invention is directed. The inventor's own patent U.S. Patent 3,706,501 having most recently issued on such a general type holder and fastener represents a distinct improvement over prior holders and fasteners, for reasons amply set forth in that patent. Prior to that patent however, as well as in that patent, the complexity of the structure for mounting substantially increases the cost thereof particularly in the assembling of the parts. For example German patent 648593 discloses the binding together of opposing flanges of stacked sheets but with the base-ends of the two springs being anchored by a special screw clamp, and also the joining ends of the opposing springs being modified by a mounted hook-element; both the screw fastener for each spring and the special hook elements are extra parts that must be bought and mounted securely by artisans, and the patent requires as a part of its operative structure a book binder having the opposing flanges. In a Swedish patent 74495, there is no good disclosure as to how the opposite springs are attached to a common strip, but it may be assumed from the figures thereof that the spring ends are welded thereto, with the strip being attached retainingly to a base member and the coil springs are secured only indirectly by threading into the spiral channel of each spring opposite ends of a common cylindrical rod member. U.S. Pat. No. 1,437,329 requires the employment of springs having a widened base of coils, while also for each spring requiring a screw clamp for screwing down into the coil of each spring for thereby binding a cover thereto on top of mounted paper, while U.S. Pat. No. 1,289,454 by the same screw principle binds each of opposite ends of the spring to respective opposite book leafs. The German patent 369115 is basically analogous in disclosure to the above noted Swedish patent 74495, except employing a bent rod the ends of which are spaced apart from one another further than the holes of the paper are spaced from one another.

SUMMARY OF THE INVENTION

Together with objects some of which are in common with the prior patented invention of U.S. Pat. No. 3,706,501, a principal object of this invention is to obtain a simplified binder and fastener of low cost of materials and of assembling thereof, and of simple and easy operation, while being of durable structure.

Another object is for the sheets or cards when bound, being such that when the sheets are bent back, the tops of each sheet are visible.

Another object is to obtain a novel base anchoring means for the base-mounting portion of each coil spring.

Another object is to obtain an improved combination of backing member and fastener for the mounting of paper, while achieving one or more of the preceding objects.

Other objects become apparent from the preceding and following disclosure.

One or more objects of the present invention are obtained by the invention as defined herein.

Broadly the invention includes a rigid or semi-rigid strip of plastic or metal of flattened shape and having 5 adjacent each of opposite ends thereof through apertures of a predetermined size, and employing for each hole a separate spiral coil spring of a diameter greater than that of the aperture, with the bottom one or more coils of the coil spring being spirally twisted into and 10 through the aperture of the strip such that one or more coils of the spring are retainingly located below the strip, while the free ends of each of the two springs have the final free-end coil twisted such as to serve as a hook for one thereof and the other serving also as either a hook or as an engaging loop of one or more coil loops, thereby avoiding the need for special attaching means on the free ends of the springs, and also merely requiring the hole (per spring) in the metal strip through which the spring of greater diameter may be 15 easily screwed and thusly impossible to pull-out without consciously un-screwing the spring therefrom, and thusly avoiding the need of special fastening screws or of bent portions of the strip or the like, while still offering the advantages of all of the prior paper fasteners but 20 at considerably reduced complexity and cost of materials and considerably reduced cost of manufacturing labor. In a preferred embodiment, a masking strip having an adhesive coating on each of opposite faces covers and secures the otherwise bare spring coils, and serves 25 as a means for neatly mounting a back leaf. Also, a preferred combination includes the bound paper, such as regular paper, plastic sheets, cardboard or the like.

THE FIGURES

35 FIG. 1 illustrates a typically bound stack of twoholed paper utilizing the novel fastener of this invention, in perspective view.

FIG. 2 illustrates in similar perspective view the 40 bound paper of FIG. 1, but with the stack opened to freely display the full face of each of opposing pages.

45 FIG. 3 illustrates an elevation plan view with partial cut-away of the bottom face of the bound paper stack and fastener backing sheet in a preferred embodiment of this invention, typically being the bottom face of the FIG. 1 disclosed embodiment.

FIG. 4 illustrates an in-part view of the metal strip end with one preferred mounting of the coil spring, the strip aperture being closely adjacent the end of the strip with the base end-coil being hooked around the end of the strip.

FIG. 5 illustrates a typical cross-sectional view of the base-end coils spiral-screwed through the aperture of the strip, it being shown that the aperture is of smaller diameter than the spring coil diameter, the strip being shown in part view. Also in cross-section the masking tape with an adhesive coating layer on each of opposite faces and the mounted back leaf are shown.

DETAILED DESCRIPTION

Unlike binders of some of the prior art discussed under the background above, the present inventive fastener and bound-paper combination does not necessarily nor preferably have a front binder leaf, this feature facilitating the removal of and/or addition of sheets from the bound stack, and the simple mechanism of binding or anchoring the base of each spring avoids the

possibility that a screw or other fastener of the types utilized by the prior art patents might strip-loose over the threads of the binding screw or the like, while the present inventive anchoring mechanism employing a hole of smaller diameter than the diameter of the helix of the spiral spring eliminates any possibility of the springs of this invention from pulling loose, as well as detaching of the spring from the back support — where utilized — is not necessary for the mounting and/or dismounting of sheets of paper or of cards, as the case may be. Because the present invention does not, in a preferred embodiment, have a front binder, the top sheet is readily available for writing thereon, and gives a clean appearance. Additionally, however, because there is no front binder adding bulk and tension against the spring in the open — turned-back — state as viewed in FIG. 2, it is more easily possible for the turned back pages to be turned completely out-of-the-way so as to display the full portion of the turned-back page as well as the full portion of the next face-up page, including the portions adjacent the bound edges of each page. Moreover, a back binder of the conventional stiff type is not required since the spring-mounting strip extending preferably between the two spring base positions is at least sufficiently rigid as to avoid the bending thereof by connecting of the joining-ends of the opposing springs which naturally serves to place bending torque onto the springs' mounting strip.

On the other hand, where a reinforcing backing leaf of rigid construction and properties is to be employed as a part of the combination, it is possible even to use two separate mounting strip bases each with a single hole therein receivable of its respective spring base to be screwed into the small aperture-hole.

In greater particularity, FIGS. 1 and 2 disclose closed-back and open-book states of a typical embodiment of a preferred combination unit 6 having top sheet 7 of a stack of sheets stacked on top of a backing sheet 12, with opposing coil springs 8a and 8b each having a last free-end coil bent into hook and ring, respectively, relationship at about perpendicular positions to the planes of the other body end-portion (of the free end) spirals, illustrated as bent end-coils 9 in the joined state in FIG. 1. In FIG. 2, the back-of-page sheet face 7b and the front-of-page face 7a of additional sheets of the stack are disclosed, both of faces 7a and 7b being fully visible and accessible for use; note that if there were a rigid front binding leaf, or if there were merely a short spring anchored in the front, the unstretched portions (i.e. remaining stretchable portions) of each of the opposing springs 8a and 8b as shown in FIG. 1 would not be available as it is available in this invention to freely slip through the respective holes 13a and 13b of stacked sheets — it being this feature which allows the FIG. 2 free turn-back of the pages to readily expose the whole of face 7b and face 7a.

In FIG. 3, there is shown an elevation plan view of the back leaf 12 of the FIG. 1 embodiment, with the back leaf 12 anchored to the strip 10 by the masking material 11 having adhesive coatings on opposite faces, being shown in cut-away in order to fully disclose (for purpose of this description) each of the masking strip 11 adhered to the preferably metal strip 10, as well as the nature of the screwed-through base-coils of spring 8b through the strip-aperture 13a' of smaller diameter than the diameter of the coils of the coil spring 8b.

In FIG. 4, there is shown an in-part view of one end of a preferred strip with the aperture (for the mounting of the spring base of the coil spring) with the base coil screwed through but having the base-end twisted to a hook-form coil 8a' and hooked through the aperture and around the strip end, thereby further anchoring the spring against twisting and/or pulling-out of the strip aperture.

FIG. 5, on the other hand, illustrates for the same type of base strip 10' typically the other end of the strip 10' with the spring end-coils 8b' screw spirally through the strip aperture of smaller diameter than that of the end-coils 8b', whereby the screwed-through coils 8b' are not withdrawable through the aperture by pulling torque on the spring. The cross-sectional relationship of the adhesive coatings 14 and 14' of the masking tape 11, and the adhered leaf 12.

It is to be understood that the above illustrative Figures are for purposes of better disclosing the nature and heart of the invention but are not intended to unduly limit the invention which includes the substitution of obvious equivalents and/or modifications and variations as would be apparent to a person of ordinary skill.

25 I claim:

1. A sheet fastener comprising in combination: two separate elongated coil springs of predetermined length and diameter of the coils thereof, each having one end-coil bent axially from the body of the coil spring as a whole such that the bent one end-coil of one of the two springs is detachably hookable into the bent one end-coil of the other of the two springs; and base means providing a flattened-face element for each of the remaining opposite end of each of said two springs defining for each respective spring remaining opposite end an aperture in its respective flattened-face element, the aperture for one of said two springs being spaced from a predetermined distance from the aperture for the other one of said two springs, each aperture being of a predetermined diameter smaller than the diameter of its respective spring's coil, the remaining opposite end of one of the two coil springs being spiraltwisted through one of said apertures such that at least one of the coils thereof is located retainingly on an opposite side of the element from the flattened-face side of the flattened-face element, and the other of the springs having its remaining opposite end spiral-twisted through the other of said apertures such that at least one of the coils thereof is located retainingly on an opposite side of the element from the flattened-face side of the flattened-face element, the base means extending lineally and being substantially rigid between said spaced apertures, whereby each of the springs are extendable upwardly through holes in opposite ends of at least one sheet of paper along a common edge of the paper and bent end-coils engagable with one-another to bind the sheet while the rigid base means retains the planar surface shape of the paper against the torque of the joined springs tending to bring-together opposite ends of the sheet, said base means being a common single element in the form of an elongated flat strip defining said flattened-face element for each said springs, said flat strip having each of opposite ends with one of said apertures located about an end adjacent thereto, the remaining opposite end of each of said springs being coil-hooked through the aperture thereof and around the strip-end edge thereof retainingly of the

spring, and a masking sheet having adhesive coatings on opposite faces adhesively mounted by one of said adhesive coatings over the back side of the strip concealable of the engaged remaining opposite end of each of the springs for each of the apertures thereof, said sheet being mounted fixedly onto the strip back side.

2. A sheet fastener of claim 1, including a rigid book-leaf sheet having an upper face along one edge thereof adhesively anchored to said mounted masking sheet.

3. A sheet fastener of claim 2, including a plurality of 10

paper sheets each having two spaced holes along a common edge thereof, with the respective holes of the plurality of sheets being aligned with one-another for the opposite ends thereof, and one of said springs extending through one series of aligned holes and the other of said springs extending through another series of aligned holes of the plurality of sheets, the plurality of sheets being in a stacked relationship to one-another.
